UNITED STATES PATENT OFFICE.

JOSEPH ARTHUR TRIMBLE AND CARL HENRY MILLER, OF PORTLAND, OREGON.

OIL-BURNER.

1,086,956.

Specification of Letters Patent.

Patented Feb. 10, 1914.

Application filed April 2, 1913. Serial No. 758,355.

To all whom it may concern:

Be it known that we, JOSEPH A. TRIMBLE and CARL H. MILLER, citizens of the United States, and residents of Portland, in the 5 county of Multnomah and State of Oregon, have invented a new and Improved Oil-Burner, of which the following is a full, clear, and exact description.

Our invention relates to improvements in 10 oil burners, and the object thereof is to provide a construction of this type which will include a mixing chamber arranged to connect at one end with a nozzle through which the fuel is supplied to be burnt, and at its 15 other end with a port to admit a mixture of air and products of combustion to mix with and heat the oil before it reaches the nozzle. The burner is adapted when supported in position to have the said port located above 20 the nozzle, with the result that the mixture of air and products of combustion which enters the burner first passes through the flame and becomes heated so as to raise the temperature of the fuel oil almost to the 25 flash point. In consequence, the burner operates with a steady flame and without the flickering or explosions so common in apparatus of this type.

Reference is to be had to the accompanying 30 drawings forming a part of this specification, in which the same characters of reference indicate the same parts in both the views.

Figure 1 is a vertical longitudinal section 35 showing a section of the fire box in which our burner is mounted in broken lines; and Fig. 2 is a top plan of our burner.

Our burner comprises a casting 1, which is mounted in the wall of the fire box of a 40 locomotive or other engine adapted to run upon liquid fuel, and it is provided at its outer end with an internally-threaded boss 2, and another internally-threaded boss 3. The first boss receives an oil pipe 4, and as 45 the burner is to be preferably of the gravity-feed type, this boss extends upward, and the pipe 4 has its lower end screwed into the same so as to permit a free flow of oil into the casting. The other boss 3 receives a 50 pipe 5 which is employed to conduct steam to the inside of the casting, this steam serving a function which will appear later. Inside the casting is a longitudinal horizontal web 6, which divides the same into internal 55 passages 7 and 8. The inner end of the casting terminates in a nozzle 9 through

which the fuel is discharged to be burned, and in rear of this nozzle and opening to the inside of the burner through the top of the casting is a port 10, this port serving for 60 the admission of a mixture of air and products of combustion which mixes with the fuel and heats it before the same passes out through the nozzle 9. The end of the web 6 adjacent the nozzle 9 is turned down 65 toward the bottom of the casting 1, as shown at 12, leaving a constricted port through which the steam flows out through the nozzle 9, and allowing a space between the nozzle and the port 10, which makes a continuation 70 of the passage 7 and serves as a mixing chamber. This mixing chamber allows of a free flow of the oil mixed with air and combustion gases from the inside of the fire box, so that the temperature of the oil is raised 75 to almost the flash point when it issues from the nozzle and is ignited.

As is well known, oil furnaces are generally so constructed that air to support the combustion is supplied from below, and it 80 will be seen that any air entering below the burner and which passes in front of the nozzle 9, at which combustion is taking place, will be heated before it can pass in through the port 10. Steam supplied 85 through the pipe 5 rushes by way of the port at 12 out through the nozzle and draws oil with it, and the passage of the oil past the port 10 will serve to create a vacuum sufficient 90 to draw in air and combustion gases from the inside of the fire-box by way of the port 10. Since, as stated above, this air must enter the fire box from below, as shown by the dotted-line arrows on Fig. 1, it will 95 pass through the flame of the burner shown and other similar burners which make up the furnace, and be highly heated before it enters the port leading to the mixing chamber 11. Consequently, the oil will have its temperature raised and may even be vaporized 100 before it issues from the nozzle 9, so that it can be ignited at once and burn with a free, steady flame as long as fuel is supplied to our burner.

Of course, as many burners will be employed as are necessary, and they will be mounted side by side in the wall of the fire box at different points, to give the desired effect. They will all, however, have their ports 10 located on top, and when a battery 110 of these burners is in operation, providing a line of jets across the interior of the fur-

nace, the heating effect of the same on the air rising from below passing through the flames of the burning fuel before reaching the port 10, can readily be appreciated.

- 5 We have found in practice that our burner is very efficient, because of the above-described operation, and the advantages which we obtain are due to heating the air and other gases before they enter the mixing 10 chamber 11, so as to raise the temperature of the oil and make the same readily ignitable. We thus accomplish a great saving of fuel, besides the uniform flame and even heating effect which our burner affords.
- 15 The above described operation is illustrative only, and we do not desire to be limited to the exact form of the burner shown and described, but wish to reserve to ourselves the right to make such changes in the shape, 20 size and arrangement of the parts as fairly fall within the scope and spirit of our invention.

Having thus described our invention, we claim as new and desire to secure by Letters 25 Patent:

1. A burner, comprising a hollow body having its upper wall at its inner end depressed to form a nozzle and provided with a port in its top adjacent the nozzle, the body 30 being further provided with a horizontal longitudinal partition dividing the same into two passages, each having at its outer end means for the connection of a pipe thereto, the inner end of the partition terminating 35 a short distance in front of the port and hav-

ing its end bent downwardly to form a constricted port for the lower passage, the space between the said port and the inner end of the nozzle forming a mixing chamber.

2. The combination of a casting having a 40 horizontal longitudinal partition or web therein dividing the same into two passages, and having a discharge opening communicating with both of said passages, said web having its end adjacent the discharge opening turned downwardly to provide free communication between the discharge opening and one of said passages, and to constrict communication between the discharge opening and the other passage, means for supplying fuel to the first passage, and means for supplying fluid to the other passage to pass through the same and said discharge opening and facilitate the flow of the fuel, and an inlet to the fuel passage in rear of 45 the discharge opening, the space between said inlet and the discharge opening forming a mixing chamber, said inlet being located so as to be on top of the casting when the same is in position to supply heated air 50 and gas to said fuel for the purpose set forth.

In testimony whereof we have signed our names to this specification in the presence of two subscribed witnesses.

JOSEPH ARTHUR TRIMBLE.
